HEATING FURNACE

Filed Oct. 8, 1930

Inventor

Peter Frantz

By Arthur F. Durand Atty.

UNITED STATES PATENT OFFICE

PETER FRANTZ, OF STERLING, ILLINOIS

HEATING FURNACE

Application filed October 8, 1930. Serial No. 487,131.

This invention relates to heaters, and more particularly to those employed for heating houses and other buildings, by means of heated air.

Generally stated, the object of the invention is to provide a novel and improved construction whereby a combustion chamber is provided in the top of the heating apparatus, together with means whereby the hot gases and products of combustion are caused to pass downwardly through passages of a radiator-like structure, the latter having vertically disposed flat sections, whereby the air to be heated is caused to pass upwardly between said sections, whereby the upwardly moving air is heated by a counterflow of downwardly moving hot gases and products of combustion, thin sheet-metal walls being interposed between the upwardly moving pure air and the downwardly moving currents of hot gases and products of combustion, whereby the pure air is caused to absorb practically all of the heat contained in said hot gases and products of combustion.

It is also an object to provide certain details and features of construction and combinations tending to increase the general efficiency and the desirability of a heater of this particular character.

To the foregoing and other useful ends, the invention consists in the matters hereinafter set forth and claimed, and shown in the accompanying drawing, in which,—

Fig. 1 is a vertical section on line 1—1 in Fig. 2 of the drawing, showing a hot-air house heater embodying the principles of the invention.

Fig. 2 is a vertical section on line 2—2 in Fig. 1 of the drawing.

As thus illustrated, the invention comprises an outer sheet-metal housing or casing 1 having a pure-air intake means 2 at the bottom, and having heated-air offtake pipes 3 at the top. The intake for the pure air can be of any suitable known or approved character,

and may take the air either from outdoors, or from the rooms to be heated, as may be desired.

Within the sheet-metal housing or casing 1 is a radiator-like structure comprising hollow sheet-metal sections 4 which are connected together and spaced apart by the rings 5, as shown, whereby a substantially cylindrical and horizontally disposed combustion chamber 6 is formed in the top of the top portion of the radiator-like structure. A gas burner 7, or other burner or heater, is disposed in the combustion chamber 6 in the manner shown. The sections 4 are also spaced apart and held together by the rings 8 in the bottom portion of the structure, whereby a cylindrical and horizontally disposed flue 9 is provided in the lower portion of this structure. Each section is composed of two sheet-metal halves, as shown, held together at their outer edges by the binding strips 10, as shown. Thus the radiator-like structures shown and described is preferably of sheet-metal throughout, whereby spaces 11 are provided between the said substantially flat and upright sections 4 of the structure.

In operation, the hot gases and products of combustion from the chamber 6 are caused to pass downwardly within the sections 4, until they finally enter the chamber 9 below, and from this chamber the said products of combustion escape through a flue 12 to a chimney or stack. The pure air entering at 2 below, passes upwardly between the sections 4, in the spaces 11, and is highly heated by absorption of the heat through the sheet-metal walls from the hot gases and products of combustion. The pure air thus heated is permitted to escape through the flues or pipes 3 to the rooms of the house or other building to be heated. Thus there is a cylindrical and horizontally disposed chamber 6 in the top portion of the radiator-like heater structure, and there is also a cylindrical and horizontally disposed chamber 9 in the bottom portion of

said structure, the two chambers being interconnected by the interior of each vertical section itself, whereby each radiator-like flue section is in the nature of a vertical flat flue connecting the upper combustion chamber with the lower outlet chamber. Therefore, the pure air passes upwardly outside of the radiator-like sections, and the air is heated substantially as it would be by an internally-heated sectional radiator structure for space heating purposes. Thus the sections form parallel down-draft flues disposed in vertical planes at right angles to the parallel axes of the said upper and lower chambers, with the spaces between said sections forming up-draft flues for the air. In this way, the air is caused to pass upwardly between the radiator-like sections from said pure air inlet to said heated air outlet, each down-draft flue opening into and communicating with the top and bottom and sides of each of said chambers.

What I claim as my invention is:

1. In a heater for heating buildings by means of heated air, the combination of an outer housing having a lower inlet for pure air and an upper outlet for heated air, and a sectional radiator-like heating structure within said housing, said radiator-like structure having vertically disposed flat metal sections spaced apart and formed to provide an upper horizontal combustion chamber and a lower horizontal outlet chamber, the two chambers being interconnected by the interior of each radiator-like section, and a burner in the upper combustion chamber, said sections forming parallel down draft flues disposed in vertical planes at right angles to the parallel axes of said chambers, with the spaces between said sections forming up-draft flues for the air, whereby the hot gases and products of combustion are caused to pass downwardly from the upper chamber to the lower chamber, while the air is caused to pass upwardly between the radiator-like sections from said pure air inlet to said heated air outlet, each down draft flue opening into and communicating with the top and bottom and sides of each of said chambers.

2. A structure as specified in claim 1, said radiator-like sections comprising duplicate sheet-metal halves held together at their outer edges, and said sections being spaced apart and interconnected by rings forming said upper and lower chambers, whereby said chambers are cylindrical and horizontally disposed, whereby each chamber is cylindrical and divided into sections by vertical spaces.

3. A structure as specified in claim 1, said radiator-like structures being composed of sheet-metal, and being flat and having upper and lower ring joint connections between them, said ring joint connections forming said upper and lower chambers, whereby each

chamber is cylindrical and divided into sections by vertical spaces.

4. A structure as specified in claim 1, said radiator-like sections being flat and having upper and lower ring connections by which they are spaced apart to form circulating passages between them for the air, whereby the air is free to circulate around said chambers, as well as between the sections, whereby each chamber is cylindrical and divided into sections by vertical spaces.

Specification signed this 3 day of Oct., 1930.

PETER FRANTZ.
